R. B. MARSH,
REVERSIBLE CAR SEAT,
APPLICATION FILED JULY 24, 1919.

1,360,966.

Patented Nov. 30, 1920.

Howson & Howson

UNITED STATES PATENT OFFICE.

RICHARD B. MARSH, OF PHILADELPHIA, PENNSYLVANIA.

REVERSIBLE CAR-SEAT.

1,360,966.

Specification of Letters Patent. Patented Nov. 30, 1920.

Application filed July 24, 1919. Serial No. 313,084.

To all whom it may concern:

Be it known that I, RICHARD B. MARSH, a citizen of the United States, residing in Philadelphia, Pennsylvania, have invented 5 Reversible Car-Seats, of which the following is a specification.

One object of my invention is to provide a car seat with relatively simple and substantial back supporting means whereby the 10 inclination of the back may be readily adjusted, the arrangement and construction being such as to insure a firm support for said back at either of its two extreme positions.

15 I further desire to provide a combination of parts for reversibly supporting a car seat back in such manner as to make possible the regulation of its movement with a view to braking or retarding it to a predetermined extent in order to prevent the violent jars or shocks otherwise given to the 20 whole seat structure when the back is shifted from one position to another.

I further desire to provide a device of the 25 above noted class with means for reducing the wear between certain of its moving parts and permitting the quick and convenient renewal of certain of them when this is necessary.

30 I also desire to provide simple and substantial means for operatively connecting the seat supporting rocker plates with the shaft connecting the side levers so that the position and inclination of the seat may be 35 altered in unison with the shifting of the seat back.

Another object of my invention is to provide a novel combination of parts for varying the inclination of a car seat back as it is 40 moved from one of its extreme positions to another, the mechanism being so assembled as to insure of such inclination being the same on both sides of a central vertical plane.

45 These objects and other advantageous ends I attain as hereinafter set forth, reference being had to the accompanying drawings, in which,—

Figure 1 is a side elevation partly in vertical section, illustrating the mechanism at one end of the seat for accomplishing the above noted objects in accordance with my invention, it being understood that such mechanism and arrangement of parts is duplicated at the opposite end of said seat;

Fig. 2 is a plan of certain of the parts shown in Fig. 1;

Fig. 3 is an elevation partly in section, on the line 3—3, Fig. 1;

Figs. 4 and 5 are sections on the lines 4—4 60 and 5—5, Fig. 1.

In the above drawings 1 represents one of the end plates of a car seat which is illustrated as of generally rectangular outline and made of pressed metal with a peripheral flange. This end plate is rigidly connected to the similar plate at the other end of the seat by two transverse members 2 constituting connecting rails of inverted U-shaped section, each flanged at its ends for 65 the reception of the bolts 3 whereby it is held in place. Said members are rigidly connected adjacent each of the seat end plates by transverse braces 4 suitably riveted in position. A rotatable shaft 5 journaled at its ends in the end plates 1, has fixed to it adjacent each plate a segmental arm 6 flanged at its outer end concentrically with the shaft 5 and provided with a series of uniformly spaced pins 7 constituting 70 teeth. These are designed to enter slots in a link 8 pivotally connected to the transverse brace 4 and having a pin or stud 9 at its outer end operative in a channel shaped guideway 10 fixed to the lower edge of the rocker plate 11. The latter is slideable longitudinally across the connecting members 2 upon which it is guided by headed rivets 12 so set therein that their heads extend over the lower flange of their coacting member 75 which is movable between them;—it being noted that said rocker plate has a substantially T-shaped section. This plate as is customary, has projecting from its upper flange two pins or studs 13 designed to fit 80 into suitable sockets 14 in the under side of the seat proper.

With this arrangement of parts a partial rotation of the shaft 5, through the segmental arm 6 and the pivoted link 8 will cause 100 longitudinal movement of the rocker plate 11 upon the end plate-connecting members or rails 2, from one extreme position, such as that shown in Fig. 1, to a similar position at the other extreme of its path of movement;—the plate 11 as is usual, having its flanged lower edge so formed as to cause its top edge and therefore the seat supported thereon, to be oppositely inclined when in 105 its two extreme positions.

For supporting the seat back, I fix to each end of the shaft 5 close to the adjacent end plate 1 an elongated arm 15 ordinarily known as a side lever and in accordance with 5 my invention, the outer end of this lever has formed in it a circular opening whose wall is beveled for the reception of a correspondingly beveled or tapered hardened steel washer 16. The standard 17, to which one 10 end of the seat back is attached, has its lower end circularly recessed (Fig. 4) and is faced adjacent to said recess for bearing upon one face of the side lever 15, to which it is held by a bolt 18 passing through it 15 and through said washer 16. The head of this bolt is counter-sunk in a boss 19 formed integral with the lower end of the standard 17 and its body is threaded into the washer 16 whose outer face is recessed for the 20 reception of a jam or lock nut 20;—it being noted that by properly adjusting the bolt 18 any desired degree of frictional resistance may be caused to oppose relative movement of the standard 17 and the side lever 25 15. To prevent relative rotation of the washer 16 and the standard 17, the first of these has projections 16^a fitting suitably placed depressions in the adjacent face of said standard.

30 Each of the plates 1 has relatively deep notches or recesses 21 formed in its upper edge concentrically with the shaft 5, for the reception of the boss 19 of its particular seat standard 17, and the arrangement is 35 such that the bottom of each recess forms a stop or abutment for firmly supporting the standard in one of its extreme positions.

For insuring that the standards 17 and therefore the seat back which they support 40 shall make the same angle with the central vertical plane through the shaft 5 in both of its extreme positions, I form the lower end of each standard with side projections and connect these with the seat end plate 45 by two similar side links 22. The preferred form of pivotal connection between each of the side levers and the end plate 1 is shown in Fig. 3, and consists of a bolt 23 having one end supported by said plate while its 50 opposite end is similarly supported by a bracket plate 24 parallel with but spaced away from said end plate. On this bolt is mounted a hardened steel boss or collar 25 which is rigidly clamped by the nut 26 between the bracket plate 24 and the end plate 1, and on this bushing the side link 22 is 55 rotatably mounted so that owing to its nature the wear of this boss is relatively small. It is particularly to be noted that 60 both the seat end plate 1 and the bracket plate 24 are slotted for the reception of each of the bolts 23 so as to permit these and therefore the lower ends of the side links 22, to be moved toward or from the shaft 5, it being obvious that with such an arrange-

ment the shifting of the position of either of the bolts while the other remains stationary, will cause such a longitudinal movement of the corresponding link 22 as will turn the standard 17 about its bolt 18 as a pivot and thus vary its inclination to the vertical.

The upper end of each of the side links 22 is formed with a circular pressed out portion 28 fitting into a correspondingly formed recess in the lower end of the standard 17 where it is pivotally held by a bolt 29 whose head is countersunk in said standard and whose nut is likewise counter-sunk in the recess in the side link.

With the above described arrangement of parts which as above noted, is the same at each end of the seat, the standard 17 and therefore the seat back carried thereby, is firmly maintained in either of its extreme positions, since its lower end is supported in the recess 21 of the end plates and is held from turning on its pivot bolts 18 by the side links 22 when said seat is moved from one extreme position to the other. The arrangement of each of the side levers 15 and links 22 is such that the former swings on its pivot from a position in which it is inclined at the desired angle on one side of a vertical plane through the shaft 5, to a second position in which it is inclined at the same angle on the opposite side of said plane. If the various parts were loosely connected by pivots as is ordinarily the case, it is obvious that when so moved the seat back and its associated mechanism would be suddenly and violently brought to rest at its other extreme position with a possibility of injury, but by setting up the bolt 18 and thereafter clamping it in the given position by the jam nut 20, any desired braking force may be exerted to retard the movement of the seat, so that it is prevented from being violently moved and then suddenly brought to rest.

I claim:

1. The combination in a seat reversing means, of a seat end plate, a bearing bracket spaced from said plate, a shaft rotatably engaging said plate; bolts extending between the end plate and the bracket, a seat back standard; a side lever fixed to the shaft and pivoted to said standard; and two side links each pivoted to the standard and having their lower ends mounted on said bolts.

2. The combination in a seat reversing means, of a seat end plate, a bearing bracket spaced from said plate, said bracket and end plate having a plurality of slots therein, shaft rotatably engaging said plate; bolts extending between the end plate and the bracket and having their ends adjustably mounted in the slots, a seat back standard; a side lever fixed to the shaft and pivoted to said standard; and two side links each piv-

oted to the standard and having their lower ends mounted on said bolts.

3. The combination in a seat back reversing means of a supporting structure; a side lever pivotally mounted thereon; a seat back standard pivoted to said side lever; and two side links respectively connecting said standard with the supporting structure, one at least of said links having its lower end 10 supported in a slot in the supporting structure to permit of its adjustment to vary the angular relation of the seat back standard and the side lever.

4. The combination in a seat reversing 15 means of a seat end plate having slots therein; a shaft rotatably engaging said plate; a side lever fixed to the shaft; a seat back standard pivoted to said side lever; two side links both pivoted to said standard; 20 and bolts entering the slots of the end plate for adjustably connecting said side links thereto.

5. The combination in a seat reversing 25 mechanism of a side plate; a shaft rotatably engaging the same; a side lever fixed to the shaft; a seat back standard pivoted to said side lever; two links pivoted to the seat back standard; a hardened bushing rotatably mounted in each of the side links; and bolts

clamping said bushing in openings in the 30 end plate for pivotally connecting said side links thereto.

6. The combination in a seat reversing 35 means of a seat end plate having a bearing bracket; a shaft rotatably engaging said plate; bolts extending between the end plate and the bracket; hardened bushings clamped by said bolts between the end plate and said bracket; a seat back standard; a side lever 40 fixed to the shaft and pivoted to said standard; and two side links each pivoted to the standard and rotatably engaging one of said hardened bushings.

7. The combination in a seat reversing 45 means of a seat end plate; a shaft rotatably engaging the same; a seat back standard connected to said shaft to cause oscillation thereof; a segmental arm fixed to said shaft, said arm having a plurality of studs thereon; a seat supporting member; with a pivotally mounted arm having a portion adapted to be engaged by said studs and having a pin operatively engaging said seat supporting member for actuating the same 50 when the shaft is turned.

55 In witness whereof I affix my signature.

RICHARD B. MARSH.
